WINDING MACHINE

Walter V. Jacobson, Apponaug, R. I., assignor to
 Universal Winding Company, Cranston, R. I.,
 a corporation of Massachusetts

Application March 9, 1944, Serial No. 525,747

21 Claims. (Cl. 242—32)

1

This invention relates to improvements in winding machines and particularly to machines for winding yarn into cops, pirns and bobbins for use in the shuttles of looms or packages for other purposes.

It is to be understood that the term "yarn" as used in the present specification and claims is intended to apply to all types of attenuated materials, whether textile or otherwise, and the term "bobbin" is employed in a broad sense to mean any type of wound package.

One object of the present invention is to provide a winding machine of the type indicated which is of simple, compact construction having relatively few moving parts.

Another object of the invention is to provide a machine of the type indicated in which the yarn is traversed on the cops or bobbins without the use of reciprocating elements liable to wear and deterioration under high speed operation.

Another object of the invention is to provide a machine of the type indicated having means for traveling the bobbins in a closed course, winding as they go, to successively bring them to a station for doffing the completed bobbins and replacing them with fresh cores or yarn-carriers to commence winding again.

Another object of the invention is to provide a winding machine of the type indicated comprising a rotary cam acting directly on a plurality of yarns to traverse them on the bobbins, means for traveling the bobbins in a closed course and means for progressively advancing the traverse during the travel of the bobbins.

Another object of the invention is to provide a machine of the type indicated which may be operated at high speed to increase its rate of production while at the same time requiring little attention on the part of the operator except to piece up broken ends and replace the supplies as they become exhausted.

Further objects of the improvement are set forth in the following specification which describes one preferred form of construction of the invention, by way of example, as illustrated by the accompanying drawings. In the drawings:

Fig. 1 is a side elevational view of the complete machine adapted for winding shuttle-bobbins;

Fig. 2 is an enlarged vertical sectional view of the same taken through the axis of the machine;

Fig. 3 is a plan view of the driving mechanism of the machine, part-sectional on line 3—3 of Fig. 2;

2

Fig. 4 is a sectional plan view of the rotary spindle-carrier on line 4—4 of Fig. 2;

Fig. 5 is a part-sectional plan view on line 5—5 of Fig. 1 showing the mounting for the stub-spindles for holding the tip ends of the yarn-carriers or wooden bobbins;

Fig. 6 is a part-sectional plan view of the creel or support for the supply packages taken on line 6—6 of Fig. 1;

Fig. 7 is a perspective view of the cam for traversing the plurality of yarns on the bobbins;

Fig. 8 is a more or less diagrammatic plan view indicating the direction of rotation of the bobbins and the direction of their travel about the axis of the machine;

Fig. 9 is a similar view showing the bobbins arranged to rotate in the opposite direction from that indicated in Fig. 8 while traveling about the axis of the machine in the same direction; and

Fig. 10 is an enlarged schematic view showing a development of the profile of the cam-track or inclined raceway for shifting the winding spindles in axial direction as they travel therearound to advance the traverse of the yarn lengthwise of the bobbins and indicating the position of one bobbin arriving at the doffing and donning station where each spindle is supplied with a fresh core or yarn-carrier.

In general, the present improved winding machine comprises a closed track, preferably of cylindrical form, having an inclined raceway around which the bobbins travel, winding as they go, with the cores or yarn-carriers mounted on vertical spindles which are rotated continuously from the driving means of the machine. A traverse-cam positioned concentrically within the circular track or raceway and rotated continuously from the machine driving means is arranged with the plurality of yarns feeding across its helical face to cause the strands to be traversed to a relatively short extent. The zone of traverse is advanced progressively longitudinally of the bobbins to form nested conical layers producing a cylindrical body of yarn with tapered or conical ends.

As the winding spindles travel around the inclined circular track they are lowered progressively to cause the layers of yarn to advance upwardly along the cores, and eventually, as each bobbin is completed, it arrives at a station for doffing it from its spindle and donning an empty core. The doffing and donning operations may be performed manually but, preferably, suitable automatically-operating means, not herein shown, are provided for this purpose.

As herein shown, the machine is provided with

eight winding spindles for mounting the cores or yarn-carriers on which the bobbins are wound, but this number is arbitrary and a greater or lesser number may be employed. The supply-cops or packages are arranged above the winding spindles in two groups supported one above the other in annular disposition about a central standard; the supply-packages preferably being "magazined" with the last delivering end from one package united to the first delivering end of a companion supply so that the yarn will deliver continuously first from one package and then from another and the exhausted supplies may be replaced with full packages without arresting the winding operation. The yarns from the supplies feed through suitable tension-devices mounted thereabove and thence lead through guide-eyes and a guiding ring to direct them downwardly to another set of guide-eyes within the traverse-cam and then laterally across its edge to the winding bobbins.

Referring to Figs. 1 and 2 of the drawings, the present bobbin-winding machine may comprise a hollow rectangular bed or base 2 resting on the floor or upon suitable standards, not shown, and surmounted by a hollow box-like housing 3. As shown in Figs. 2 and 3, the housing 3 may be fastened to the top wall 4 of the bed 2 by means of bolts 5 passing through ears 6 on the housing and screwed into threaded holes in the base. The housing 3 encloses the driving mechanism of the machine and is provided on its side with an opening 7, see Fig. 3, for permitting access thereto. The opening 7 may be covered by a door 9 hinged to the side of the housing 3, see Fig. 1, and normally held closed by means of a hand-latch 14 engageable with a lug 15 on the side of the housing.

A circular opening 18 is provided in the top wall of the housing 3 adjacent one end thereof, see Fig. 2. The opening 18 is counterbored to form a circular ledge 19 upon which is seated the lower end of a cylindrical track or raceway 20 formed with an upper cam-like rim, described later in detail. As shown in Fig. 2, the track 20 may be secured in place on the casing 3 by means of screws 21 passing through holes in the flange surrounding the ledge 19 and screwed into threaded holes in the sides of the track.

Fastened to the top wall 4 of the base 2 by means of screws 24 and extending upwardly therefrom in concentric relation to the opening 18 in the housing 3 is a hollow column or standard 25. As shown in Fig. 2, the upper portion of the standard 25 is reduced in diameter to receive the hub 29 of a rotatable member 30, a bushing 31 being employed in the bearing between these parts to reduce wear. The member 30 is provided at its lower end with a pair of circumferential flanges 33 and 34 which are bored at spaced intervals to provide bearing openings 35 and 36 extending in parallel relation to the axis of the member. The openings 35 and 36 may be provided with bushings 38 for mounting the vertical winding spindles 40 of the machine, described in detail hereinafter, which are adapted to rotate and slide vertically therein. Fastened to the lower flange 34 of the member 30 by means of screws 46 is a worm-gear 47 provided with teeth on its periphery, see Figs. 2 and 3.

Mounted upon the upper end of the member 30 is a rotary member or carrier 50 for supporting the plurality of vertical winding spindles 40, see Figs. 2 and 4, which are adapted to re-

volve therewith within the track 20. The carrier 50 is of annular form with an inwardly-directed flange 51 at its lower end seated upon the upper end of the member 30 and secured 5 rotatively therewith by means of screws 52. The carrier 50 is provided with a plurality of vertical cylinders 55 arranged in circumferentially-spaced relationship and communicating with the interior of each cylinder is a vertical slot 56 in its side. The hollow cylinders 55 contain piston-like elements or sleeves 58 adapted to slide vertically therein. Each sleeve 58 is provided with a reduced bore at its upper end with a bushing 59 therein for rotatably supporting the upper end 10 of a winding spindle 40. Each spindle 40 is provided with an enlarged head 41 seating upon the upper end of the bushing 59. A cup-like recess or depression 42 in each head 41 is adapted to receive the enlarged butt *b* of a wooden bobbin 15 for rotating the latter in the manner and for the purpose as explained hereinafter. The lower portion of each spindle 40 is journaled in the alined bushings 33 in the bores of the flanges 33 and 34 of the member 30, previously referred to, and mounted on each spindle is a small pulley 43 positioned between the flanges. As shown in Figs. 2 and 3, the spindles 40 are formed with relatively long keyways 45 and the pulleys 43 have keys 44 engaging therein to rotatively connect them therewith while permitting the spindles to slide vertically in their bearings. Fastened to the side of each sleeve 58 by means of screws 62 is a key 63 which projects outwardly through the vertical slot 56 in the side of the cylinder 55 to restrain the sleeve from rotation while permitting it to slide axially therein. A headed stud 64 having a reduced threaded shank screwed into a tapped hole in the key 63 on each sleeve 58 carries a roller 65 journaled thereon and arranged to rest upon and roll along the upper cam-edge of the track 20, see Figs. 2 and 10.

A rod 68 attached to the key 63 on each sleeve 58 by screws 69 extends upwardly for mounting an arm 70. As shown in Figs. 2 and 5, each arm 70 is formed with a split hub 71 which is adjustably clamped to the rod 68 by means of binder-screws 72. Each arm 70 terminates in a cylindrical boss 73 provided with a bore 74 axially aligned with its registering spindle 40 and rotatable in the bore is a stub-spindle 75. As shown at the left in Fig. 2, the stub-spindle 75 carries a head 76 at its lower end which is recessed to receive the tip end of a core or wooden bobbin 15 *b*. The stub-spindle 75 normally is urged downwardly to engage the tip end of the wooden bobbin 15 in the head 76 by means of a helical spring 77 surrounding the spindle with its ends abutting the head 76 and the under side of the boss 73. Downward movement of the stub-spindle 75 is limited by the engagement of a washer 78, fastened to its upper end by a screw 79, with the upper end of the boss 73. It will be understood from the foregoing description 60 that the several winding cores or wooden bobbins 15 are held between the heads 41 of the winding spindles 40 and the heads or cups 76 on the stub-spindles 75 so that when the spindles 40 are rotated through driving means, described later, the bobbins likewise will be rotated at relatively high speed.

The yarns *y* are supplied to the winding bobbins from a magazine creel arranged above the winding mechanism and supported on a skeleton column or framework comprising a plurality of

vertical rods 80 rising from the spindle-carrier 50. Mounted on the rods 80 are two circular shelves or brackets 81 and 82, the upper one of which is shown in plan view in Fig. 6. The bracket 81 preferably is of skeleton form having spokes radiating from a central ring 83 for supporting its outer rim which is provided with a series of supply-holders comprising disks 84 with suitable spindles 85 rising from the axes thereof. The supply-packages P may be in the form of cross-wound cones of large bulk which are seated on the spindles 85 with their bases resting on the disks 84. As shown in Fig. 6, the edge of the rim of the bracket 81 is formed with recessed guide-eyes 86 for the trailing ends of the yarns from the upper sets of supplies P to direct them downwardly for connection to the leading ends of the supply-packages P' of the lower set.

Mounted on the upper ends of the vertical rods 80 is a circular plate 87, to which are attached a plurality of tension-devices 88, equal in number to the number of supply-packages in each series. The tension-devices 88 may be of any usual construction; for example, of the grid-type as shown in Fig. 1, and associated therewith are lower and upper guides 89 and 90 for directing the yarns from the supplies P between the tension-grids. Supported above the plate 87 is a bracket 91 on which are mounted a series of resilient arms 92 which radiate therefrom and carry pigtail or round thread-guides 93 at their ends. The guides 93 are adapted to receive the yarns leading from the tension-devices 88 to direct them downwardly to a series of pigtail-guides 94 projecting from the rim of the upper bracket 81. From the pigtails 94 the yarns are arranged to feed downwardly through a gathering ring 95. The gathering ring 95 is mounted on the rods 80 by means of bosses 96 and is formed at its center with an axial hub 97. Held in the axial hub 97 is a depending vertical rod 98 mounting a hub or boss 99 at its lower end. The hub 99 supports a series of radially-projecting pigtail-guides 100 by means of which the yarns y are adapted to be guided to the spindles 40 to wind on the cores or wooden bobbins b. The supply-packages P' of the lower series are mounted on supply-holders similar to those previously described carried on the bracket 82 and the leading ends of the yarns y' therefrom are fastened to the trailing ends y from the packages P of the upper set so that the yarns may deliver continuously first from the upper supplies and then from the lower supplies, and vice versa, while exhausted supplies are being replaced by full packages. The complete assembly of the creel and yarn-guiding means described above is thus carried on the column comprising the rods 80 which are supported from the spindle-carrier 50 to rotate therewith as the winding bobbins b travel around the trackway 20.

In winding filling bobbins for use in the shuttles of looms and for some other kinds of packages, the yarn is distributed on the cores or yarn-carriers with a relatively short traverse and the zone of traverse advanced progressively from the base to the tip end of each core. In the present machine the yarn is distributed on the core or wooden bobbin b with an extent of traverse considerably less than the length of the bobbin by means of a rotary cam 105, shown in detail in Fig. 7. The cam 105 is of dish-shape as constituted by a circular bottom wall 106 and a cylindrical rim 107, the upper edge of which is of helical contour or profile. As shown in Fig. 2, the bottom wall 106 of the traverse-cam 105 is

fastened by screws 108 to a disk 109 fast on the upper end of a vertical shaft 110. The upper end of the cam-shaft 110 is journaled in a bearing 111 mounted at the upper end of a tubular support 112. The lower end of the tube 112 is fitted to the reduced upper terminal portion of the stationary standard 25. The lower end of the cam-shaft 110 is journaled in a bearing 113 formed in the top wall 4 of the base 2. The cam-shaft 110 projects downwardly below the bearing 113 and carries a stepped-face pulley 115 which is keyed thereto and held axially thereon by a set-screw 117. The shaft 110 may be driven continuously by a belt 118 or by gearing connected to the main driving mechanism of the machine described hereinafter.

During the winding operation the bobbins are gradually lowered with respect to the traverse-cam 105 so that the zone of traverse will be shifted progressively toward the tip of the cores b to eventually produce bobbins B of the shape shown at the left in Figs. 2 and 10. This gradual lowering of the bobbins is effected by revolving the spindles 40 around the track 20 with the rollers 65 on the sleeves 58 riding on its inclined raceway. Fig. 10 illustrates a development of the track 20 and indicates the manner in which the rollers 65 ride along its upper cam-shaped rim. As shown in this latter view, the upper beveled edge of the track 20 is formed with a short horizontal rest 125 and a sharply-inclined portion 126 which slopes downwardly therefrom to merge into a raceway 127 of lesser inclination. The raceway 127 extends throughout substantially five-sevenths of the entire circumference of the track 20 and then merges into an upwardly-inclined portion 128 which connects with the rest 125. At the start of the winding operation the roller 65 for the spindle 40 of each bobbin b will ride off from the rest 125, travel down the sharply-inclined portion 126 and onto the gradually inclined raceway 127, at which point the winding is commenced. As the bobbins revolve in a path concentric to the axis of the cam-shaft 110 the roller 65 on the sleeve 58 carrying the spindle 40 for each bobbin will ride downwardly along the raceway 127 of the track 20 to cause the bobbin to be gradually lowered whereby to advance the zone of traverse of the yarn upward on the core b.

The driving mechanism for the machine is enclosed in the housing 3 and may comprise a prime-mover such as a reversible electric motor 130 shown at the right in Figs. 2 and 3. A pulley 131 on the shaft of the motor 130 may be connected to drive a vertical countershaft 122 by means of a belt 133 passing over a pulley 134 on the countershaft. The countershaft 122 is journaled in a lower bearing 135 formed in the top wall 4 of the base 2 with its upper end supported in a bearing 136 projecting laterally from a standard or bracket 137 bolted to the base of the machine at 138. The countershaft 122 is connected to drive the rotary spindle-carrier 50 through a train of gearing driven from a worm 139 keyed to the countershaft. The train of gearing is mounted on a bracket or standard 140 bolted to the top of the base 2 and carrying suitable bearings for the shafts of the gears. The worm 139 meshes with a gear 141 carrying a pinion 142 fast on its shaft 143 and meshing with a larger gear 144 fast on a shaft 145. The shaft 145 carries a pinion 146 meshing with a larger gear 147 fast on a shaft 148. Keyed to the shaft 148 is a gear 149 meshing with a larger gear 150 fast on a shaft 151. The shaft 151 carries a pinion 153 mesh-

ing with a gear 154 fast on a shaft 155. The gear 154 drives through a pair of change-gears 156 or 157, the shafts of which are mounted in an adjustable bracket 158 pivoted to rock about the shaft 155. The gear 156 is mounted fast on a shaft 160 journaled in the bracket 158 and carrying a worm 162. The worm 162 is adapted to mesh with the worm-wheel 47, previously described as being fastened to the member 30 which mounts the spindle-carrier 50 for rotation therewith.

The change gear 157, previously mentioned, has its stud-shaft 163 rotatably mounted in the bracket 158 and fast on the inner end of the shaft is a worm 164. The shaft 155 is adjustably mounted in an arcuate slot 165 provided in the upper end of the standard 140 in concentric relation to the axis of the shaft 151. The bracket 158 is also provided with an arcuate slot 166 concentric to the axis of the shaft 155. A bolt 167 extends through both slots 165 and 166 and a nut 168 screwed onto the threaded end of the bolt is adapted to clamp the bracket 158 in different positions of adjustment, see Figs. 2 and 3. With the bracket 158 in the position illustrated in Fig. 2, the gear 157 rotates as an idler during the drive through the gear 156 and worm 162 to the worm-wheel 47. In other instances, however, the gear 157 may be shifted into position to adapt the worm 164 fast on its shaft 163 to drive the worm-wheel 47, whereupon the worm 162 will be disengaged from the worm-wheel 47. To effect this change in the drive the nut 168 on the bolt 167 is loosened and the bracket 158 moved toward the right, as viewed in Fig. 2, with the shaft 155 sliding in the slot 165 in the standard 140. The bracket 158 then may be rocked upwardly to carry the worm 164 into alignment with the worm-wheel 47, after which the bracket may be shifted toward the left to engage the worm with the teeth on the worm-wheel. With the worm 164 engaged with the worm-wheel 47 the nut 168 is tightened on the bolt 167 to clamp the bracket 158 in its adjusted position. In this latter position of adjustment the worm-wheel 47 may be rotated from the worm 164 in the same direction as that in which it is driven by the worm 162 when the direction of rotation of the countershaft is reversed by reversing the motor 130. The purpose of this arrangement is to provide that the spindle-carrier 50 will always turn in the same direction even though the winding spindles are driven in reverse direction in some instances for the purpose hereinafter explained.

As the spindle-carrier 50 is rotated to revolve the bobbins about its axis, thereby traveling them around the trackway 20, the spindles 40 are rotated by means of the pulleys 43 keyed to their lower ends. The pulleys 43 are rotated by means of an endless belt 170 encircling the series and driven by a flanged pulley 171 at the upper end of the countershaft 122, see Figs. 2 and 3. The belt 170 is maintained under tension by means of an idler pulley 173 journaled at the end of an arm 174 fastened to the upper end of a bushing 175 surrounding the countershaft 122 and projecting upwardly from the bearing 136 on the standard 137. The arm 174 has a split hub 176 surrounding the bushing 175 with a binder-screw 177 therein for clamping the arm in position to maintain the idler pulley 173 pressing against the slack side of the belt 170.

The traverse-cam 105 is rotated at a relatively fast rate of speed during the travel of the wind-

10

ing spindles 40 and the cores *b* mounted thereon around its circumference, the cam being driven by its shaft 110 carrying the stepped pulley 115 previously referred to. The pulley 115 is connected by the belt 118 to a smaller pulley 169 on the lower end of the countershaft 122, this latter pulley having stepped faces arranged opposite to the stepped faces on the pulley 115 so that by shifting the belt 118 thereon the speed of rotation of the cam 105 may be varied to alter the character of the wind in accordance with different materials being wound. A forked belt-shipper 180 within the confines of the bed 2, see Fig. 1, is pivoted to its forward side by means of a rod or shaft 181. A handle 182 on the outer end of the shaft 181 provides a convenient means for rocking the belt-shipper to shift the belt 118 on the pulleys 115 and 169.

15

The complete bobbin-winding machine having been described in detail its method of operation is as next explained: In preparing the machine for operation several determining factors are first ascertained and the operating elements adjusted in accordance with requirements. For example, the required number of turns or coils of yarn to be deposited on the bobbins during each traverse stroke is determined. In the present machine the speed of the spindles is constant and therefore to secure the correct ratio between the 20 rotative speed of the bobbins and the traversing rate of the yarn to produce bobbins having a definite character of wind, the belt 118 for driving the traverse-cam 105 may be shifted on the stepped faces of the pulleys 115 and 169 in accordance with requirements. Assuming that it is required to deposit seven coils or turns of yarn on each bobbin during each traverse stroke in either direction, the belt 118 is positioned to pass around the pulleys 115 and 169 in the manner 25 shown in Fig. 2 of the drawings to provide a fourteen-to-one ratio between the rotative speed of the spindle 40 and the speed of the traverse-cam 105. With this latter arrangement the bobbins will be wound with what is termed a "seven wind." For producing bobbins having a "five wind," as is sometimes desirable, the ratio between the rotative speed of the bobbin-spindles 40 and the traverse-cam 105 should be ten-to-one and to obtain this relationship the belt 118 may 30 be shifted onto the opposite faces of the pulleys 115 and 169.

35

Another factor to be considered in preparing the machine for operation is whether the bobbins are to be wound with a regular or reverse wind 35 in accordance with the type of twist in the yarn. For producing bobbins with a regular wind they are rotated in clockwise direction so that when the yarn is subsequently drawn off over the end it will unwind in clockwise direction. On the other hand, it is sometimes desirable to produce a reverse wind by rotating the bobbins in counter-clockwise direction to provide that when the yarn is drawn off over the end it will unwind in counter-clockwise direction. With a standard three-phase A. C. motor of squirrel-cage type a switch 40 in its circuit may be used to control the direction of rotation of its armature whereby to adjust the machine for producing either regular or reverse-wound bobbins. For the purpose of illustration let it be assumed that a regular wind is desired and that the armature of the motor 130 is rotated in counterclockwise direction as viewed in Fig. 2, to cause the spindles 40 to rotate in clockwise direction as viewed in Fig. 8.

45

With the armature-shaft of the electric motor 50

130 rotating in counterclockwise direction and with the worm 162 in mesh with the worm-wheel 47 on the spindle-carrier 50 the latter will be rotated in counterclockwise direction as viewed in Fig. 3 whereby to slowly travel the spindles 40 in an annular course with their rollers 65 rolling on the upper face of the stationary track 20. At the start of a winding operation the cores or wooden bobbins *b* are applied to the spindles 40 and the yarn-strands *y* attached thereto as they arrive at the donning station in regular sequence. The motor 130 drives the countershaft 122 and through the connections described above the spindles 40 will be rotated on their own axes at relatively high speed and revolved at a slow rate about the axis of the track 20 while the traverse-cam 105 is rotated at a speed in proper ratio with that of the spindles. Assuming that an empty spindle 40 has reached the position shown at F in Fig. 10 with its roller traveling up the sharp incline 128 and onto the elevated rest 125 of the track 20, the operator may thread the appropriate yarn-strand *y* through the proper pigtail-guide 100 and place it across the head 41 of this spindle. The head *h* of a bare bobbin-core *b* next may be placed in the recess 42 of the spindle-head 41 to clamp the yarn between it and the head while the tip of the core is inserted in the recess in the head 76 of the stub-spindle 75 as shown at the right in Fig. 2 and indicated at C in Fig. 10. During this donning operation the spindle 40 will have been elevated by the engagement of the roller 65 on the bearing sleeve 58 with the high point or rest 125 of the track 20 and thus the yarn leading from the guide 100 to the head *h* of the bobbin will be restrained from contact with the edge of the rotating traverse-cam 105. Referring to Fig. 8, during the short interval that the spindle 40 is elevated toward the rest 125 on the track 20 it is displaced away from the driving belt 170 and therefore will not be rotated thereby. As the spindle-carrier 50 continues to rotate slowly in counterclockwise direction, as viewed in Fig. 8, to convey the core *b* to the station represented by the reference character D in Figs. 8 and 10 the roller 65 will travel down the inclined portion 126 of the track 20 and onto the less inclined raceway 127 thereof. As the core *b* approaches the position indicated at D in Fig. 10 the pulley 43 at the lower end of the spindle 40 will be carried into the path of the driving belt 170 to be engaged and rotated thereby. As the spindle 40 and core *b* mounted thereon are rotated the yarn *y* will be caused to wind on the core and since the yarn feeds across the edge of the rotating traverse-cam 105 it will be traversed back and forth lengthwise of the core with an extent of traverse equal to the rise and fall of the cam-face.

During the travel of the first bobbin from the donning position indicated at C to the initial winding position represented at D in Figs. 8 and 10 another spindle 40 will have been advanced to the station C to receive a bare bobbin-core *b*. This core *b* is applied between the heads 41 and 76 of the spindle 40 and stub-spindle 75, respectively, and another yarn-strand *y* attached thereto in the manner explained above in connection with the first bobbin considered.

As the winding operation progresses the operator of the machine may continue to place empty cores *b* on the successive winding spindles 40 as the latter arrive at the station C. During the travel of each spindle 40 from the position indicated at D to that represented at E their rollers

70
75

65 will ride down the gradual slope of the raceway 127 on the track 20 whereby to continuously lower the bobbins with respect to the traverse-cam 105. Due to this progressive displacement of the cores *b* with respect to the traverse-cam 105 the zone of traverse, indicated by dash-lines in Fig. 10, will be advanced lengthwise of the cores *b* from their heads *h* toward their tip-ends to eventually form filling bobbins *B* such as that shown at the extreme left in Fig. 10. As the winding on each bobbin is completed during its travel from the position indicated at D to that represented at E the bobbin is returned to the doffing and donning station to arrive at station C. During the advance of each finished bobbin *B* from position E to position C its spindle 40 will be elevated as the roller 65 on its bearing sleeve 58 rides up the sharply-inclined return portion 128 of the trackway 20. During this upward movement of the spindle 40 as indicated at F in Fig. 10 its pulley 43 will be withdrawn laterally from contact with the driving belt 170, as shown in Figs. 3 and 8, to arrest the rotation of the spindle and bobbin and thereby discontinue

45

As the roller 65 for each spindle 40 rides up onto the rest 125 the operator may sever the length of yarn leading to the bobbin, doff the full bobbin *B* from the spindle and replace it with an empty core *b* while at the same time clamping the end of the yarn from the supply between the head *h* of the fresh core and the head 41 on the spindle to prepare this particular spindle for another winding operation. It will be observed from the above explanation that the present bobbin-winding machine operates continuously to travel the bobbins in an annular course during the winding operation and to advance them individually into position for doffing and replacement by fresh cores *b*. While for the purpose of the present disclosure the doffing and donning operations have been explained as being performed manually, it is contemplated that automatically-operated means be provided for effecting these functions; but since such mechanism forms no part of the present invention it is not herein shown or described.

During the winding operation the central column or standard comprising the vertical rods 88 is rotated slowly with the spindle-carrier 50 to which the rods are attached so that the supply-packages *P* mounted at the upper end of the column will revolve therewith. When the supply of yarn in one package *P* is exhausted the connected strand delivering from a new package arranged below, or above as the case may be, will feed downwardly to the bobbin *B* being wound. A fresh supply-package *P* then may be substituted for the empty cone-tube or other yarn-carrier and the leading end of its strand tied to the trailing end of the yarn in the package from which the yarn is delivering. In this manner the supply of yarn is maintained continuous with the result that the winding operation may proceed without interruption.

When it is desired to produce bobbins having a reverse wind, so-called, the direction of rotation of the spindles 40 is reversed to cause them to turn in counter-clockwise direction as indicated in Fig. 9. To effect this change in direction of rotation of the spindles 40 the direction of rotation of the countershaft 122 is reversed. That is to say, the countershaft 122 and pulley 171 will be driven in counterclockwise direction, as viewed in Fig. 3, to cause the belt 170 to travel

in the direction indicated by the arrows in Fig. 9. To effect this reverse rotation of the spindles 49 the switch of the electric motor 130 may be shifted to reverse the direction of rotation of its armature shaft and pulley 131. Referring to Fig. 9, when the bobbins 5 are rotated in counterclockwise direction the yarn-strands will be wound thereon in the same direction so as to draw off over the ends thereof in counterclockwise direction as is sometimes desired. This is especially desirable when certain kinds of yarns are to be used for weaving since it is possible to obtain a more uniform tension with less kinking of the yarn as the latter delivers from the shuttle.

Regardless of the direction of rotation of the spindles 49 during the winding operation, the spindle-carrier 50 must always rotate in counterclockwise direction, as viewed in Fig. 4, to insure that the rollers 65 will travel in the proper direction on the track 20. When the direction of rotation of the countershaft is to be reversed the nut 168 on the bolt 167 is loosened and the bracket 159 rocked about the shafts 154 and 155 to mesh the worm 164 with the worm-wheel 47 on the spindle-carrier 50, after which the nut is tightened to hold the bracket in adjusted position. With the various parts adjusted in this manner the gear 158 will be driven in the opposite direction from that first described to drive its companion gear 157 in reverse direction and turn the worm 164 to rotate the carrier 50 in counterclockwise direction to effect proper cooperation between the rollers 65 and track 20.

Referring to Fig. 10, the sloping raceway 127 of the track 20 may be formed with a profile of greater or lesser inclination for different lengths of bobbins or its cam-face may be varied in other ways as required for different types of packages, all within the scope and purview of the present invention. For example, to wind bobbins having parallel-sided cylindrical body portions on tapered cores it is necessary to gradually increase the amount of yarn deposited on the bobbin from start to finish of the winding operation. To produce this latter form of winding the cam-shaped upper edge of the trackway 127 may have less inclination throughout the greater portion of its length so that as the rollers 65 travel from station D to station E the rate of descent of the bobbins will be progressively lessened throughout the winding operation.

It will be observed from the foregoing specification that the present invention provides a bobbin-winding machine which is of simple, compact construction while being highly efficient in operation. It also will be observed that in the present machine comprising a plurality of winding spindles arranged to travel about the centrally-located cam, common to all the spindles, the traversing means is reduced to utmost simplicity, thereby eliminating the usual reciprocating yarn-guides and other parts liable to wear and deterioration in use. It will be observed further that the means for advancing the traverse of the yarn lengthwise of the bobbins is common to all of the several winding spindles and avoids the use of screw-threaded progression wheels, ratchet-devices and other complicated mechanisms. Thus, the present improved machine provides for winding a plurality of bobbins continuously at high speed by the use of extremely simple mechanism while requiring little attention on the part of the operator.

While I have shown and described the improved bobbin-winding machine as embodied in

a preferred form of construction, by way of example, it is to be understood that various modifications may be made in the structure and arrangement of its parts without departing from the spirit or scope of the invention. Therefore, without limiting myself in this respect, I claim:

1. In a winding machine, means for supporting textile cores arranged in a circle, means for rotating said cores, a rotary cam having a helical face, means for rotating said cam, means for feeding a plurality of yarns across the helical face of the cam to cause it to traverse the yarns lengthwise of the cores to wind cops or bobbins thereon, means for traveling the cores circumferentially of the cam, and means operative during the travel of the cores for effecting relative axial displacement between the cores and cam to progressively advance the zone of traverse longitudinally of the cores.

2. In a winding machine, a plurality of winding spindles supported in annular arrangement, a cylindrical cam having a helical face, means for rotating the winding spindles, means for rotating the cam, means for guiding a plurality of yarn-strands across the helical face of the cam to the winding spindles to cause the yarn to be traversed longitudinally thereof to wind cops or bobbins thereon, means for traveling the spindles circumferentially of the cam, and means operated thereby for effecting relative displacement between the spindles and cam axially of the spindles during their travel around the cam.

3. In a winding machine, a cylindrical traverse cam having a helical face, a plurality of winding spindles arranged concentrically of said cam, means for rotating the cam, means for rotating the winding spindles, means for guiding a plurality of yarn-strands across the helical face of the cam to the several winding spindles to cause the yarn to be traversed longitudinally thereof, and auxiliary cam-operated means for effecting relative displacement between the traverse-cam and spindles axially thereof to progressively advance the traverse of the yarn-strands lengthwise of the spindles to wind filling bobbins thereon.

4. In a winding machine, a rotary cam having a helical face, a plurality of winding spindles supported in annular arrangement surrounding said cam, means for guiding a plurality of yarn-strands to the interior of the cam and directing them across the helical face thereof to feed to the winding spindles, means for rotating the spindles, means for rotating the cam to traverse the yarn axially of the spindles to wind cops or packages thereon, means for circulating the winding spindles in a closed course, and means for effecting a relative axial displacement between the spindles and cam to advance the traverse of the yarn lengthwise of the spindles.

5. In a winding machine, a rotary cam having a helical face, a plurality of winding spindles for mounting textile cores, means for supporting the spindles in annular arrangement surrounding said cam, means for traveling the spindles circumferentially of the cam, means for guiding a plurality of yarn-strands across the helical face of the cam to cause them to feed to the cores, means for rotating the spindles to wind the yarn on the cores, and means for rotating the cam to cause it to traverse the yarn-strands lengthwise of the cores mounted on the spindles.

6. In a winding machine, an inclined track, a plurality of winding spindles arranged adjacent the track and provided with means engaging

therewith, means for rotating the spindles, a single means for traversing yarn on the plurality of spindles, and means for effecting relative advancing movement between the spindles and track to cause the zone of traverse to be shifted lengthwise of the spindles.

7. In a winding machine, a circular track provided with an inclined raceway, a plurality of winding spindles arranged concentrically of the track and provided with means engaging the raceway, means for rotating the spindles, means for traversing yarn on the spindles, and means for effecting relative revolution between the track and spindles to cause the latter to be shifted axially to advance the zone of traverse of the yarn lengthwise of the spindles.

8. In a winding machine, a circular track provided with an inclined raceway, a plurality of winding spindles arranged concentrically of the track, means for rotating the spindles, means for traveling the spindles around the track, means for traversing yarn-strands on the spindles, and means connected with said spindles and engaging the inclined raceway on the track for axially moving the spindles during their travel therearound to cause the zone of traverse to be shifted axially of the spindles.

9. In a winding machine, a stationary inclined track, a plurality of winding spindles arranged adjacent the track, means for rotating the spindles, means for traversing yarn on the spindles, means for traveling the spindles relatively of the track, and means on the spindles engaging the track for effecting gradual axial movement of the spindles whereby to progressively advance the zone of traverse lengthwise of the spindles.

10. In a winding machine, a circular track provided with an inclined raceway, a plurality of winding spindles arranged concentrically of the track and provided with means engaging the raceway, a single traversing element for distributing yarn on the several winding spindles, and means for effecting relative progression between the track and spindles to cause the latter to be shifted axially to advance the zone of traverse of the yarn lengthwise of the spindles throughout the winding operation.

11. In a winding machine, a circular track provided with an inclined raceway, a plurality of winding spindles arranged concentrically of the track and provided with means engaging its raceway, a rotary traverse cam arranged concentrically of the track and adapted to simultaneously distribute a plurality of yarn-strands on the individual winding spindles, and means for effecting relative progression between the track and spindles to cause the latter to be shifted axially to advance the zone of traverse of the yarn lengthwise of the spindles throughout the winding operation.

12. In a winding machine, a circular track provided with an inclined raceway, a plurality of winding spindles supported in annular arrangement adjacent the track and provided with means engaging its raceway, means for rotating the spindles, a rotary cam arranged coaxially of the track and provided with a helical rim, means for guiding a plurality of yarn-strands to the interior of the cam and directing them across the helical rim thereof to feed to the winding spindles, means for rotating the cam to cause its helical rim to traverse the yarn-strands axially of the spindles, and means for effecting relative progression between the track and spindles to cause the latter to be shifted axially to advance the zone of trav-

erse of the yarn lengthwise of the spindles throughout the winding operation.

13. In a winding machine, a stationary circular track provided with an inclined raceway, a rotary carrier arranged coaxially of the track, a plurality of winding spindles supported on the carrier annularly of the track and provided with means engaging its raceway, means for rotating the spindles, a rotary cam disposed within the track and formed with a helical rim, means for guiding a plurality of yarn-strands to the interior of the cam and across its helical rim to feed to the winding spindles, means for rotating the cam to traverse the yarn axially of the spindles, and means for rotating the carrier to travel the spindles around the inclined raceway of the track whereby to cause the spindles to be shifted axially to advance the zone of traverse of the yarn lengthwise thereof throughout the winding operation.

14. In a winding machine, a hollow cylindrical track provided with an inclined raceway, a rotary carrier arranged coaxially of the track and formed with a plurality of openings extending in parallel relation to its axis, a sleeve slidable in each opening, a winding spindle journaled in each sleeve, means for rotating the carrier to travel the spindles around the track, a cam disposed within the track and formed with a helical rim, means for guiding a plurality of yarn-strands to the interior of the cam and across its helical rim to feed them to the spindles, means for rotating the spindles, means for rotating the cam to traverse the yarn axially of the spindles, and rollers on each bearing sleeve travelable on the inclined raceway of the track to gradually shift the sleeves and spindles axially to advance the zone of traverse of the yarn lengthwise of the spindles.

15. In a bobbin-winding machine, a circular track provided with an inclined raceway, a carrier arranged coaxially of the track, a plurality of spindle-carrying members slidably mounted on the carrier, a winding spindle rotatable on each member and adapted to mount a bobbin, a rotary cam disposed within the track and provided with a helical rim, means for guiding a plurality of yarn-strands to the interior of the cam and across its rim to feed them to the bobbins, means for rotating the spindles, means for rotating the cam to traverse the strands on the bobbins to an extent substantially less than the length of the bobbins, means for rotating the carrier to travel the bobbins around the track, and rollers on the spindle-carrying members travelable along the inclined raceway of the track to gradually shift the spindles axially relatively of the traverse-cam whereby to progressively advance the zone of traverse of the yarn lengthwise of the spindles to produce filling-wound bobbins.

16. In a bobbin-winding machine, a plurality of winding spindles supported in annular arrangement, means for rotating the spindles, means for simultaneously traversing yarn-strands lengthwise of the spindles to wind bobbins thereon, means for traveling the spindles in a closed course, and means for progressively shifting the spindles axially during their traveling movement to advance the zone of traverse of the yarn-strands lengthwise of the bobbins.

17. In a bobbin-winding machine, a plurality of winding spindles supported in annular arrangement, means for rotating the spindles to wind bobbins thereon, a cam for simultaneously

traversing yarn-strands lengthwise of the spindles with an extent of traverse substantially less than the length of the bobbins, means for traveling the spindles in a closed course, and means for progressively shifting the spindles axially during their traveling movement to advance the zone of traverse of the yarn-strands lengthwise of the bobbins.

18. In a bobbin-winding machine, a circular track provided with a downwardly-sloping raceway, an upwardly-inclined raceway and a horizontal rest therebetween, a plurality of winding spindles arranged annularly of the track and adapted to support bobbin-cores, means for rotating the spindles, a traverse-cam within the track for simultaneously traversing a plurality of yarn-strands on certain of said bobbin-cores, means for rotating the cam, means for traveling the spindles around the track, rollers connected to the spindles and travelable along the track, 10 said spindles being progressively lowered axially as their rollers ride along the downwardly-sloping raceway to advance the zone of traverse of the yarn lengthwise of the bobbin-cores and to elevate the spindles during the travel of the rollers along the upwardly-inclined raceway onto the rest for doffing the bobbins from their respective spindles.

19. A bobbin-winding machine comprising a circular track formed with a downwardly-sloping raceway and an upwardly-inclined raceway, a rotary carrier, winding spindles mounted annularly of the carrier for vertical sliding movement thereon and adapted to support bobbins, a rotary cam within the track for traversing yarn-strands on the bobbins to an extent substantially less than the length of the bobbins, means for rotating the carrier, spindles and traverse-cam, and a roller connected to each spindle and adapted to roll upon the track during rotation 30 of the carrier, said spindles being progressively 35

lowered axially during the travel of the rollers along the downwardly-sloping raceway to advance the zone of traverse of the strands lengthwise of the bobbins and said spindles being elevated during the travel of the rollers along the upwardly-inclined raceway.

20. A bobbin-winding machine comprising a circular track formed with a downwardly-sloping raceway and an upwardly-inclined raceway, a rotary carrier, a plurality of winding spindles arranged annularly of the carrier for vertical sliding movement thereon, said spindles being adapted to support bobbins, a cam within the track for traversing yarn-strands on the bobbins, means for rotating the traverse-cam, means for rotating the spindle-carrier, rollers on the spindles engageable with the track for progressively shifting the spindles axially during the travel of their rollers along the downwardly-sloping raceway to advance the zone of traverse lengthwise of the bobbins and acting to elevate the spindles during the travel of the rollers along the upwardly-inclined raceway to permit the removal of the bobbins from their respective spindles, and means for rotating the spindles during the travel of their rollers on the downwardly-sloping raceway and arrest their rotation during the travel of the rollers along the upwardly-inclined raceway.

21. In a winding machine, a plurality of winding spindles, means for rotating the spindles to wind bobbins thereon, means for traveling the spindles in a closed course, a raceway having inclined portions cooperating with the spindles during their travel to cause them to be shifted axially, and means for traversing yarn on the spindles during their travel and axial shifting movement whereby to wind the yarn in conical layers progressing longitudinally of the bobbins.

WALTER V. JACOBSON.
